UNITED STATES PATENT OFFICE.

CARLO MARS BAZZEGHIN, OF ORANGE, CONNECTICUT.

UNION-OVERGARMENT.

1,334,129.

Specification of Letters Patent.

Patented Mar. 16, 1920.

Application filed December 14, 1918. Serial No. 266,739.

To all whom it may concern:

Be it known that I, CARLO MARS BAZZEGHIN, a citizen of the United States, residing at Orange, in the county of New Haven and 5 State of Connecticut, have invented certain new and useful Improvements in Union-Overgarments, of which the following is a specification.

The present invention comprehends generally improvements in that class of inventions known as apparel and more particularly relates to an improved union overgarment.

It is the principal aim and object of this 15 invention to provide an article of wearing apparel of the above mentioned character wherein the component parts for covering the body, limbs and head of the wearer are all either joined together or formed integral 20 to consequently provide a sanitary union garment especially adapted for use by surgeons, cooks, dairymen, druggists, etc.

More particularly the present invention contemplates the provision of a garment of 25 the above mentioned character wherein improved elastic inserts are connected between the top of the hood, the rear connecting portion and the collar and positioned on opposite sides of the face of the wearer to insure 30 of a proper maintenance of the hood and collar when the garment is being worn and at the same time permitting of the wearer to move the head and preventing germs, et cetera, from passing into the hood.

35 Among the other aims and objects of the present invention may be recited the provision of a garment of the above mentioned character wherein the construction is simple, the cost of production low and the efficiency 40 high.

The improvements in the details and arrangement of parts will be apparent from an inspection of the accompanying drawings, in connection with the specific description 45 hereinafter contained, and wherein the preferred embodiment of the invention is disclosed for the purpose of imparting a full understanding of the invention.

The invention is clearly illustrated in the 50 accompanying drawings, in which:

Figure 1 is a perspective view showing the garment applied,

Fig. 2 is a fragmentary side elevation of the hood portion, and

55 Fig. 3 is a perspective detail showing the

invisible fastening means at the slit in the body of the garment.

Similar characters of reference are employed in all of the above described views, to indicate corresponding parts.

Referring now, more particularly, to the accompanying drawings there is provided an improved garment formed of suitable material and consisting of a body portion 1 having sleeves 2 attached thereto while 65 formed integral with the body portion is a trouser or pantaloan portion 3. A collar 4 is formed integral about the neck opening in the body portion while integral with the collar portion is a hood or cap 5. The opposing side portions near the front of the hood are cut away while elastic inserts 6 are secured as by stitches 7 to the adjacent edges of the top of the hood the rear connecting portion 8 between the top of the hood and 70 the back of the collar and to the upper edges of the collar as shown particularly in Figs. 1 and 2 to insure of a proper snug fitting of the hood and the collar when the garment is applied, the elastic inserts 6 being snugly 75 arranged against the cheeks of the wearer to prevent germs, et cetera, from passing into the hood and thence to the interior of the garment.

In order that the garment may be quickly 85 applied and removed the front of the body portion 1 is provided with a slit 9 which extends from the front of the collar to a point slightly above the crotch of the trouser portion 3 and the portions immediately adjacent the slit are positioned in overlapping 90 relation with each other and have separable fasteners 10 connected thereto for the detachable fastening of the portions immediately adjacent the slit 9 in overlapping 95 relation, as is apparent.

It is believed in view of the foregoing description that a further detailed description of the operation of the invention is entirely unnecessary. Likewise, it is believed that 100 the advantages of the invention will be readily apparent. However, it is also to be understood that this sanitary union garment is especially adapted for use by surgeons, dairymen, druggists, et cetera.

Still further embodiments of the invention than those herein especially defined may be resorted to as conditions or preferences may dictate, as may be in keeping with the hereto appended claim.

Having thus fully described the invention, what is claimed as new and desired to be secured by Letters Patent, is:

A garment including a body enveloping portion and a head covering portion united at the rear by a connecting portion, the body portion, the head covering portion and the connecting portion being of non-yieldable fabric, and a rubber insert between the body enveloping portion, the head covering por-

tion and the connecting portion and united thereto to hold the head portion securely upon the head and to closely engage the face and ears of the wearer of the garment irrespective of possible contact with moisture 15 or damp fumes.

In testimony whereof, I affix my signature hereto.

CARLO MARS BAZZEGHIN.
